(57) **CLAIM**

The ornamental design for a combination slide clamp and occlusion clamp actuator, as shown and described.

DESCRIPTION

FIG. 1 is a perspective view of a combination slide clamp and occlusion clamp actuator showing my/our new design; FIG. 2 is a top plan view thereof, the bottom plan view thereof being identical; FIG. 3 is a right side elevational view thereof, the left side elevational view thereof being identical; FIG. 4 is a front elevational view thereof; FIG. 5 is a rear elevational view thereof; FIG. 6 is a perspective view thereof similar to FIG. 1 showing by phantom lines a broken fluid delivery tube which does not constitute a portion of my/our new design; and, FIG. 7 is a perspective view thereof similar to FIG. 1 showing by phantom lines a broken fluid delivery tube which does not constitute a portion of my/our new design.
